UNITED STATES PATENT OFFICE

148,197

DESIGN FOR A CONDIMENTS HOLDING DISH OR SIMILAR ARTICLE

Angelo P. Therrios, Jersey City, N. J.

Application February 14, 1946, Serial No. 126,568

Term of patent 7 years

(Cl. D44—10)

To all whom it may concern:

Be it known that I, Angelo P. Therrios, a citizen of the United States of America, residing at Jersey City, in the county of Hudson in the State of New Jersey, have invented a new, original, and ornamental Design for a Condiment Holding Dish or Similar Article, of which the following is a specification, reference being had to the accompanying drawings, forming a part thereof.

I claim:

The ornamental design for a condiment holding dish or similar article, substantially as shown.

ANGELO P. THERRIOS.
